UNITED STATES PATENT OFFICE.

FERNAND CARBENAY, OF PARIS, FRANCE.

VARIABLE CONTROLLING ELEMENT.

Application filed August 29, 1921, Serial No. 496,541, and in France May 8, 1920.

As well known, in installations in which variable inductances are used for adjusting the circuits traversed by high frequency currents, the unused portions of such inductances cause energy losses unless care is taken to eliminate all connections between such portions and the portion that is in service. For this purpose, the inductances are usually divided into a certain number of sections which the operator may connect in series or insulate by means of plugs or specially operated switches. Each section is composed of a certain number of divisions which cooperate with the controlling member, wiper or switch arm. Each adjustment necessitates two successive operations; the operation of the wiper or the handle, and the operation of the divider into sections.

The object of the present invention is to devise an arrangement in which only the controlling member is operated to cut into service or divide into sections the different parts of the inductance coil. The arrangement is produced in such a manner that, in response to the normal operation of the controlling member, a cam-like member having two projections is actuated to perform the function of the switch.

The invention will be more readily understood by reference to the enclosed drawings in which Fig. 1 represents the cam above referred to, and Fig. 2 represents the provision of such a cam in combination with the other elements of an inductance that may be controlled by means of a multiposition switch.

Figures 3, 4 and 5 represent modified forms of my invention.

The special element F (Fig. 1) is preferably of copper or spring bronze, and is shaped like a clover leaf. Its thickness is usually equal or slightly greater than that of the movable wiper by means of which the switch arm engages the terminals. Section B of this member is perforated at A, and the member F may rotate around a screw passing through this hole. The corners of sections C and D are suitably rounded and are connected by means of a curved piece E. These sections perform the function of cams and contact making members.

The circuit arrangement and the operation of the sectional divider is illustrated in Fig. 2 showing the assembly of the apparatus. The inductance L is divided for example, into three parts M, N, P. At a

certain number of points, these parts are connected to the terminals 1, 2, C₁, 3, 4, 5, 6, C₂, 7, 8, 9, arranged to be engaged by the arm Q of the switch that is connected to the outgoing terminal T₂ of the apparatus. The incoming terminal T₁ is connected with the end R of the inductance coil. In this manner, a variable inductance is provided which has the special feature that the outgoing ends of sections M and N are connected with terminals C₁ and C₂ respectively separated from terminals 3 and 7 which are connected, respectively, with the incoming ends of the succeeding sections N and P. The special cams F' and F'' for automatically dividing into sections, are provided near the terminals in such a manner that, in response to a certain angular displacement around their axis, the cams may establish or break the connection between two sections of the inductance. The axis of the cam is electrically connected with the incoming end of an inductance section, while the part C' or C'' is moved into one of its positions in which it contacts with the terminal connected to the outgoing end of the said section. The contact wiper of the switch moves the cam from one position into another. When the switch is moved from left to right, it presses upwards the projections B' and B'' when it engages terminals 3 and 7. Connection is now established between C₁, C' and C₂, C'' and the successive sections of the inductance are cut into service. When the arm Q is moved from right to left (decreasing inductances), the projections C'' and C' are pushed back and the unused sections of the inductance are automatically isolated.

These dead terminals may be eliminated by covering with or constructing of insulating material one of the projections of the special cam. The outgoing end of one section is adapted to be connected with the terminal engaged by the conducting projection of the cam, and the incoming end of the succeeding section is connected with a conducting portion of the cam, preferably its shaft.

It should be noted that, the cutting of the cams and the shaping of the ends of the contact making rods or wipers must be such that one may slide over the other with minimum friction. Furthermore, the cams must be secured in a manner to prevent free rotation around their axis, and if necessary,

stops may be provided to limit the angular movement of the cams.

Although in Fig. 2 an inductance is shown that is divided into three sections, obviously, the number of the sections may be increased at will. Without departing from the spirit of the invention, the automatic section divider may be made to operate in the above described manner without the necessity of arranging the projections C and B as contact makers. One method of attaining this result is to arrange the cam as shown in Figure 3, wherein the arm C''' may be constructed of conducting material and the arm D''' of insulating material.

These projections could be arranged in different planes to be engaged by a suitable member the movement of which is controlled by the switch. The contact between the terminal and the shaft or the body of the cam is secured through the agency of a wiper suitably mounted on the cam as shown in Figure 4, wherein the cam C is provided with a wiper arm W adapted to make and break contact, which cam is controlled by a projection H mounted on the wiper arm Q.

It should be noted also that this system is applicable also in case variable inductances are controlled by a wiper having a rectilinear movement as shown in Figure 5, wherein K and K' represent adjacent sections of a coil, a variable amount of which is to be cut in by the slider S operating on guide G. The slider S is provided with a projection H which is arranged to operate the cam C. This system of dividing into sections may be utilized also for other purposes than controlling variable inductances. It may be used in all cases where it is desired to divide into sections electrical circuits in response to the operation of a controlling switch.

Having described my invention, what I claim is:

1. A variable controlling element comprising a plurality of sections, said sections being provided with a plurality of connecting conductors, a regulating member for establishing contact with the terminal points of said conductors, a member electrically connected to one end of a section and having a portion adapted to contact with a terminal point of another section, said member having a portion adapted to be engaged by the regulating member to electrically connect said sections together and disconnect them entirely from each other.

2. A variable electrical controlling element comprising a plurality of sections, said sections being provided with a plurality of connecting conductors, a regulating member for establishing contact with the terminal points of said conductors, a pivoted cam electrically connected to one end of a section, said cam having an arm adapted to be engaged by said regulating member when moved in one direction and a second arm adapted to be engaged when the regulating arm is moved in the opposite direction.

3. A variable electrical controlling element comprising a plurality of sections, said sections being provided with a plurality of connecting conductors, a regulating member for establishing contact with the terminal points of said conductors, a pivoted cam electrically connected to one end of a section, said cam having an arm adapted to be engaged by said regulating member when moved in one direction and a second arm adapted to be engaged when the regulating arm is moved in the opposite direction, one of said arms being insulated and a contact controlled by the movement of said cam adapted to engage a terminal of a second section to make or break connection between said sections connected with said cam.

FERNAND CARBENAY.
